[57] CLAIM

The ornamental design for a radiant stove heater, as shown and described.

DESCRIPTION

FIG. 1 is a top plan view of a radiant stove heater showing our new design;

FIG. 2 is a side elevation view thereof, the opposite side being a mirror image of that shown;

FIG. 3 is a top, right side perspective view thereof;

FIG. 4 is a top, left side perspective view thereof; and

FIG. 5 is a bottom plan view thereof.

The broken lines showing items fitted to the heater are for illustrative purposes only and form no part of the claimed design.
